UNITED STATES PATENT OFFICE.

AUGUST A. RUSTEBERG, OF CHICAGO, ILLINOIS, ASSIGNOR, BY MESNE ASSIGNMENTS, TO THE CHAMPION KEROSENE-BURNER COMPANY, OF KENTON, OHIO, A CORPORATION OF OHIO.

GENERATOR AND BURNER.

1,320,928.

Specification of Letters Patent.

Patented Nov. 4, 1919.

Application filed October 26, 1918. Serial No. 259,857.

To all whom it may concern:

Be it known that I, AUGUST A. RUSTEBERG, a citizen of the United States, and a resident of the city of Chicago, in the county of Cook and State of Illinois, have invented certain new and useful Improvements in Generators and Burners; and I do hereby declare that the following is a full, clear, and exact description of the same, reference being had to the accompanying drawings, and to the numerals of reference marked thereon, which form a part of this specification.

This invention pertains to a fuel gas generator and burner adapted for use in connection with stoves or furnaces and wherein a plurality of starting burners are formed on the top of a generating burner and below an oil supply generating pipe and a carbureting pipe to initially heat the oil supply pipe to vaporize the oil therein, which vaporized oil is mixed with air in the carbureting pipe to form a fuel oil-gas to be burned to heat an annealing furnace.

25 The process of oil-gas generation, after being started by the starting burners, is carried on by the generating burner which also burns the oil-gas already generated.

It is an object of this invention to construct a fuel gas generator and burner wherein the vaporizing and the carbureting pipes are adapted to be heated simultaneously by either the starting burners or the generating burners.

35 Another object of the invention is the construction of a generator and burner having the starting and the generating burners positioned below the control valve and the vaporizing and mixing pipes.

40 It is also an object of this invention to provide a generator and burner wherein an annealing furnace is adapted to be heated by a valve controlled burner receiving a fuel gas from a carbureter which is heated by burner flames which also act to vaporize oil in a generating pipe before the vaporized oil is admitted into the carbureter where air is carbureted with said vaporized oil to form the fuel gas.

45 It is a further object of this invention to construct a generator and burner wherein oil vaporizing and mixing mechanisms are simultaneously heated by the same burners.

50 It is furthermore an object of the invention to construct a generator and burner

having a carbureter provided with a valve at each end thereof for controlling the admittance and the discharge of gas therefrom.

It is an important object of this invention to construct a generator and burner having the carbureter mounted above the oil vaporizer to permit fuel oil-gas mixed therein to be fed downwardly to a generating burner and to a heating burner.

Other and further important objects of the invention will be apparent from the disclosures in the drawings and specification.

The invention (in a preferred form) is illustrated in the drawings and hereinafter more fully described.

On the drawings:

Figure 1 is a front elevation of a generator and burner embodying the principles of this invention, and shown associated with a furnace shown in section.

Fig. 2 is a top plan view of the device with the furnace omitted.

Fig. 3 is a section taken on line 3-3 of Fig. 2, with parts in elevation.

Fig. 4 is an end view of the device.

Fig. 5 is an enlarged section taken on line 5-5 of Fig. 2.

Fig. 6 is an enlarged detail section of the controlling valve taken on line 6-6 of Fig. 4, showing parts in elevation, and with parts omitted.

Fig. 7 is an enlarged detail section of the burner valve taken on line 7-7 of Fig. 2, with parts in elevation.

Fig. 8 is an enlarged top plan view of the generating burner, showing the starting burner troughs.

As shown on the drawings.

The reference numeral 1, indicates an annealing arch or furnace, lined with fire-bricks or fire-stones 2, which form the inner wall of the furnace. Formed in the upper central portion of the furnace is a heating burner passage 3, into which projects the lower end of a burner jet, pipe or tube 4, the upper projecting end of which is externally threaded and engaged in an internally threaded arm or collar 5, integrally formed on the lower part of a valve casing 6. Adjustably or slidably disposed within the valve casing 6, is a valve head or piston 7, to which one end of a valve stem or rod 8, is attached. The valve stem 8, pro-

95

100

105

110

jects longitudinally through the valve casing 6, and outwardly through a longitudinally passaged externally threaded sleeve 9, integrally formed on one end of said casting. Disposed against the outer end of the sleeve 9, is a packing 10, which surrounds the valve stem and is held in position by means of a washer 11, and a cap 12, which is removably threaded upon said sleeve with the valve stem projecting through the closed apertured end thereof. The outer end of the valve stem 8, is squared as denoted by the reference numeral 13, to receive a handle or tool to 10 permit actuation of the valve stem and the valve head attached thereto. Threaded into the open end of the valve casing 6, is one end of a sleeve coupler, union or nipple 14, the end of which affords a stop or a valve seat for the valve head 7.

Threaded upon the other end of the union 14, is one end of a Y-pipe fitting comprising a main pipe section 15, and a downwardly inclined pipe arm 16, integral therewith. Alined with the pipe section 15, and the valve casing 6, is a carbureting or mixing tube or pipe 17, one end of which is threaded into the other end of the pipe section 15, while the other or air intake end 20 is open.

Rigidly mounted upon one side of the furnace 1, is a bracket or support 18, upon the horizontal top of which is secured a long hollow casting 19, whose interior forms a gas chamber and having an inclined end wall 20, at its inner end provided with an inlet opening 21. As clearly shown in Figs. 5 and 8, the top of the gas chamber casting 19, is formed to provide two parallel generating 25 burners 22, separated by a middle starting burner trough 23, in which a wick 24, is placed. Formed to the outside of each of the generating burners 22, is an outside starting burner trough 25, having a wick 26, disposed therein. Closing the inner ends of the starting burner troughs is a low transverse supporting wall 27, integrally formed on the casting near the inner end thereof. Integrally formed transversely on the top 30 of the outer end of the casting 19, is an apertured supporting wall 28. Threaded into the opening 21, of the casting is the lower end of a sleeve coupler or union 29, the upper end of which is threaded into the pipe arm 16. The wicks 24 and 26, of the middle and side starting burners are adapted to be saturated with kerosene or any other suitable hydro-carbon to permit the wicks to be lighted for starting the operation of the device.

A curved, looped or U-shaped oil supply vaporizing or generating pipe, is disposed above the generating burners 22, and the starting burners 23 and 25. Said generating pipe embraces a curved yoke or elbow

30, which rests upon the top of the supporting wall 27, below the inner end of the carbureting tube 17. Secured in one end of the elbow 30, is the inner end of a long pipe arm 31, which is disposed directly over one of the generating burners 22, and has its other end projecting through an opening for the purpose in the supporting wall 28. Engaged in the other end of the elbow 30, is a shorter pipe arm 32, which is longitudinally disposed directly above the other generating burner 22, with its outer end terminating to the inside of the supporting wall 28, and a little beyond the outer intake end of the carbureting tube 17. The generating pipe is positioned directly above the casting 19, with the pipe arms 31 and 32, parallel to and above the generating burners 22, and between the middle starting burner 23, and the respective side starting burners 25, so that the flames from said burners may strike and heat the same. Connected to the outer projecting end of the vaporizing arm 31, by means of an elbow fitting 33, is an oil feed pipe 34, which is provided with a regulating valve mechanism 35.

Attached upon the outer end of the vaporizing arm 32, to the inside of the supporting wall 28, is an oil vapor control valve mechanism comprising an upwardly directed arm or pipe 36, the lower end of which is curved to permit the same to be threaded upon the arm 32. The upper end of the pipe arm 36, is open and is internally threaded to removably receive a plug 37, to permit cleaning of the interior of the valve when the plug is removed. Integrally formed at right angles across the upper portion of the pipe arm 36, and communicating with the interior thereof is a valve casting or sleeve 38, which is alined with the carbureter 17, and has the outlet end thereof disposed directly opposite or in front of the open air intake end of the carbureter. Removably threaded into the outlet end of the valve casting 38, is a valve plug 39, provided with a tapered vapor gas outlet opening. Adjustably seated in the valve outlet opening is the tapered valve end or needle point 40, of a valve stem or rod 41, which projects longitudinally through the valve casting 38, and has the outer end thereof squared as denoted by the reference numeral 42, to receive a tool or handle to permit rotation of the valve stem to open or close the valve outlet opening. Integrally formed on the valve stem 41, intermediate the ends thereof is a threaded shank 43, which is adapted to thread through an externally and internally threaded sleeve nipple 44, provided with an integral nut collar 45, intermediate the ends thereof adapted to contact the other end of the valve casting 38, to close the same. The outer end of the nipple 44, is ground to receive a packing 46, thereagainst. The pack-

ing 46, surrounds the valve stem 41, and is securely held in position by means of a washer 47, and a cap 48, which is threaded upon the outer end of the nipple. The closed 5 end of the cap 48, is centrally apertured to permit the valve stem to project therethrough.

The operation is as follows:

To start the generator and burner the 10 wicks 24 and 26, of the middle and side starting burners are first saturated with kerosene or any other suitable hydro-carbon, and then lighted. The heat from the resulting flames acts to rapidly heat the vaporizing arms 31 and 32, and also the carbureter 17, which is positioned above said starting burners and said vaporizing arms. By 15 opening the valve 35, kerosene or any other suitable hydro-carbon is supplied to the carbureter 17, passing around through the yoke 30, and into the vaporizing arm 32. The heat from the burning starting burners 23 and 25, heats the arms 31 and 32, thus 20 causing the oil within said arms to be vaporized to form an oil vapor.

The controlling valve stem 41, is rotated by applying a tool on the squared end 42, thereof, thereby causing the threaded shank 43, to move outwardly through the nipple 44, simultaneously withdrawing the valve point 40, out of the valve outlet opening in the plug 39. The oil vapor is thus permitted to flow from the arm 32, through the valve pipe 36, and escape through the open 35 valve outlet. The air is thoroughly mixed with the oil vapor during their passage through the carbureter, thus producing or generating an oil-gas fuel.

In starting the apparatus oil-gas fuel 40 produced by mixing air with the heated oil vapor in the carbureter, flows through the Y-fitting 15—16, into the gas chamber in casting 19 and escapes through the burner openings of the generating burners 22, and is 45 lighted. The resulting flames from the burning generating burners pass upwardly around the vaporizing arms 31 and 32, to heat the same and the carbureter 17, which is disposed thereabove, thereby continuing to vaporize the oil in the looped generator, or 50 vaporizer 30—32. The process of oil-gas fuel generation is thus perpetuated, and the starting burners, of course go out after the oil with which the wicks 24 and 26 were 55 saturated has burned up.

After the generator and burner has been set into operation to produce a continuous supply of oil-gas fuel, as described, the annealing furnace 1, is heated by pulling outwardly on the furnace burner valve stem 8, thereby moving the valve head 7, and opening the furnace burner valve to permit oil-gas fuel from the pipe section 15, to 60 flow through the union 14, and the valve 65 casing 6, into the burner-jet 4, and out of

the burner opening 3. The escaping oil-gas fuel from the burner opening 3, is lighted from the interior of the furnace and the resulting flame heats the interior of the furnace.

With the parts arranged as described, it will be noted that all of the starting burners and the two generating burners when operating act to heat not only the vaporizer 30—32, but also serve to heat the carbureter 17, thereby acting to keep the vaporized oil heated before and after it enters the carbureter where the heated oil vapor is mixed with air to form the oil-gas fuel.

When it is desired to shut off the generator and burner the oil supply control valve 35, is first closed to discontinue the oil supply to the vaporizer. The generating burners 22, are then allowed to burn until the oil-gas fuel supply is used up. The oil vapor 80 valve and the furnace burner valve may be closed when desired or adjusted to effect any desired opening thereof, by operating the respective valve stems. The generator and burner parts are removably connected 85 to one another, and are further provided with removable plugs to permit cleaning of any of the generator and burner parts when necessary.

I am aware that many changes may be 90 made and numerous details of construction may be varied through a wide range without departing from the principles of this invention.

I claim as my invention:—

1. In a generator and burner of the class described, a looped oil vaporizer, starting burners under the arms thereof adapted to initially heat the same to vaporize the oil therein, generating burners disposed between said starting burners and below the arms of said vaporizer, a carbureter connected with said generating burners and disposed thereabove and above said vaporizer, an oil supply valve connected to one end of 105 said vaporizer, an oil vapor valve connected to the other end of said vaporizer to control the discharge of oil vapor into said carbureter to be mixed with air to form an oil-gas adapted to be used as a fuel in said generating burners to continue the process of 110 oil-gas generation.

2. In a generator and burner of the class described, a looped oil supply and vaporizing pipe, starting burners positioned under 115 the arms thereof for initially heating the same to vaporize the oil therein, an oil control valve connected with one end of said looped pipe, an oil vapor valve connected to the other end of said looped pipe to control the discharge of oil vapor, a carbureter disposed above said looped pipe and above 120 said starting burners adapted to receive the oil vapor from said oil vapor valve and mix the same with air to form an oil-gas, gen- 125

erating burners disposed below said looped pipe and said carburetor, means connecting said carburetor and said generating burners to permit the generated oil-gas to pass into 5 the generating burners and be burned to heat the looped pipe and said carburetor to continue the process of oil-gas generation, and a burner mechanism connected with said means to receive oil-gas therefrom to 10 be used as a fuel in said burner mechanism.

3. In a generator and burner of the class described, an oil vaporizing pipe, starting burners therebelow for initially heating the same to vaporize the oil therein, an oil control valve connected with said pipe, an oil vapor valve also connected with said pipe to control the discharge of oil vapor therefrom, a carburetor above said pipe adapted to receive the oil vapor and carburet air there- 20 with to form an oil-gas, generating burners disposed below said pipe and carburetor, means connecting said carburetor and said generating burners to permit oil-gas to pass into the generating burners to be burned 25 as a fuel to heat said pipe and carburetor to continue the process of oil-gas generation, a burner valve mechanism connected therewith to receive and burn oil-gas from 30 said burner valve mechanism when the same is open.

4. The combination with a furnace, of a burner therein, a valve mechanism connected therewith, a carburetor and a generating burner connected with said valve mechanism, starting burners, an oil supply pipe disposed between said generating burner and said carburetor adapted to be initially heated by said starting burners to vaporize the oil 35 therein, means for controlling the flow of oil 40 vapor from said pipe into said carburetor to be mixed with air to form an oil-gas adapted to be used as a fuel in said generating burner to continue the process of oil-gas generation 45 and as a fuel in said furnace burner when said valve mechanism is open to cause heating of said furnace.

5. In a device of the class described a tank, a plurality of generating and starting burners formed on the top thereof, supporting walls integrally formed on said tank, a vaporizer supported thereby and disposed above said generating and starting burners, a carburetor connected with said tank and 50 disposed above said vaporizer and said generating and starting burners, and controlling valves connected with said vaporizer.

6. In a device of the class described a vaporizer, a carburetor thereabove, and a unitary casting below said vaporizer and carburetor comprising a gas tank, supporting walls for said vaporizer formed on said tank, a middle starting burner trough forming part of the top of said tank, a generating 60 burner integrally formed on each side of

said middle starting burner, and a side starting burner trough integrally formed to the outside of each of said generating burners.

7. In a burner mechanism of the class described the combination with a valve controlled furnace burner, of a carburetor, means connecting said carburetor and said furnace burner, a generating burner connected to said means, starting burners adjacent said generating burner, a vaporizer 70 supported above said generating burner and said starting burners and below said carburetor, and controlling valves connected with said vaporizer. 75

8. In combination, a gas chamber having 80 gas escape apertures; a mixing tube disposed above said chamber; a heating burner; means connected with the outlet end of said tube for conducting gases to said burner; a lateral connection between said tube and 85 said chamber near the discharge end of the tube to admit gas from the tube to the chamber; and a generating pipe adjacent the chamber and below the mixing tube adapted to be heated by gas escaping from 90 said apertures, and to discharge gas into the inlet end of said tube, substantially as described.

9. In combination, a gas chamber having 95 gas escape apertures; a mixing tube disposed above said chamber; a heating burner; means exterior to the chamber connected with the outlet end of said tube for conducting gases from said tube to the heating burner; a lateral connection between 100 said tube and said chamber near the discharge end of the tube to admit gas to the chamber; and a horizontally disposed looped generating pipe supported below the mixing tube and adjacent the chamber so as 105 to be heated by the gas escaping from said apertures, said generating pipe discharging into the inlet end of said mixing tube, substantially as described.

10. In combination, a casting having an 110 interior gas chamber and gas outlet apertures; a mixing tube disposed above said casting; a lateral connection between said tube and said chamber near the discharge end of the tube to supply gas to the chamber; a heating burner; means for conducting gases away from said tube to the heating burner independently of the chamber and extending beyond the connection of said tube with the chamber; and a generating 115 pipe extending between the chamber and the mixing tube, and discharging into said inlet end of said tube, substantially as described.

11. In combination, an elongated hollow casting having an interior gas chamber and 120 gas escape apertures; a mixing tube disposed above said chamber and supported on the casting; a lateral connection between said tube and said chamber near the discharge end of the tube; a heating burner; 125

means for conducting gases from said tube independently of the chamber to the heating burner, said means extending beyond the said connection of the tube with the chamber; and a horizontally disposed looped generating pipe supported upon the casting, and extending between the chamber and the mixing tube, and discharging into the inlet end of said tube, substantially as described.

12. In combination, an elongated hollow casting having an interior gas chamber and gas escape aperture; a mixing tube supported on the casting above the chamber; a heating burner separate from the casting; a discharge pipe connected with the outlet end of said mixing tube to conduct gases to said heating burner; a tubular connection between said chamber and the mixing tube adjacent the connection of the discharge pipe therewith; a horizontally disposed generating pipe supported upon the casting above the chamber and below the mixing tube in position to be heated by the gases issuing from said apertures; a jet at the outlet end of said generating pipe to direct oil vapors into the inlet of the mixing tube; and valved oil supply means connected with the inlet end of said generating pipe, substantially as described.

13. In combination, a furnace having a gas opening in its top; a hollow casting adjacent the furnace having gas-escape apertures; a mixing tube above the casting; a discharge pipe connected with the outlet end of said mixing tube and conducting gases therefrom to the gas inlet of the furnace; a connection between said casting and the mixing tube, to admit gas into the casting; a horizontally disposed generating pipe supported below the mixing tube in position to be heated by the gases issuing from the apertures in the casting; means at the outlet of said generating pipe for directing a jet of vapor from the generating pipe into the inlet of the mixing tube; and means connected with the inlet end of said generat-

ing pipe to supply oil thereto, substantially as described.

14. In combination, a furnace; a hollow casting thereon having gas escape apertures; a mixing tube located above the casting; a pipe connected with the outlet end of said mixing tube and conducting gases to the furnace; a connection between said casting and the mixing tube adjacent the connection of the said pipe therewith to admit gas into the casting; a horizontally disposed looped generating pipe supported on the casting below the mixing tube and adapted to be heated by the gases issuing from the said apertures; a jet aperture in the outlet end of said generating pipe for directing vapor into the inlet end of the mixing tube; and means connected with the inlet end of said generating pipe to supply oil thereto, substantially as described.

15. In combination, a furnace; a hollow casting mounted on the furnace having an interior gas chamber and gas escape apertures; a mixing tube supported on said casting and located above the chamber; a discharge pipe connected with the outlet end of said mixing tube and conducting gases into the top of the furnace; a lateral tubular connection between the mixing tube and said chamber to supply gas to said chamber; a horizontally disposed looped generating pipe supported on the casting and below the mixing tube in position to be heated by the gases issuing from the said apertures; a jet head connected with the discharge end of said generating pipe to direct vapor into the inlet end of the mixing tube; and valved means connected with the inlet end of said generating tube to supply oil thereto, substantially as described.

In testimony whereof I have hereunto subscribed my name in the presence of two subscribing witnesses.

AUGUST A. RUSTEBERG.
